CLAIM

I claim the ornamental design for an electric horn and sound machine, as shown and described.

DESCRIPTION

FIG. 1 is a front perspective view of a new ornamental design for electric horn and sound machine.

FIG. 2 is a top plan view of FIG. 1.

FIG. 3 is a bottom plan view of FIG. 1.

FIG. 4 is a front plan view of FIG. 1.

FIG. 5 is a rear plan view of FIG. 1.

FIG. 6 is a left side view of FIG. 1; and,

FIG. 7 is a right-side view of FIG. 1.

The broken lines shown depict unclaimed environment and form no part of the claimed design.
